L. K. SNELL,
HYDROCARBON MOTOR,
APPLICATION FILED NOV. 17, 1915.

1,239,138.

Patented Sept. 4, 1917.

UNITED STATES PATENT OFFICE.

LYLE K. SNELL, OF DETROIT, MICHIGAN, ASSIGNOR TO CADILLAC MOTOR CAR COMPANY, OF DETROIT, MICHIGAN, A CORPORATION OF MICHIGAN.

HYDROCARBON-MOTOR.

1,239,133.

Specification of Letters Patent. Patented Sept. 4, 1917.

Application filed November 17, 1915. Serial No. 61,899.

To all whom it may concern:

Be it known that I, LYLE K. SNELL, a citizen of the United States, and resident of Detroit, Wayne county, State of Michigan, have invented certain new and useful Improvements in Hydrocarbon-Motors, of which the following is a specification:

This invention relates to hydrocarbon motors, and particularly cooling systems, as applied thereto.

One of the objects of this invention is to improve circulating systems in general and particularly cooling systems as applied to internal combustion engines, where it is desired to maintain the cooling medium at a uniform temperature.

Another object is to provide a simple and efficient arrangement of valve mechanisms for controlling the flow of liquid in a circulating system.

Another object is to provide a positive means for draining a liquid circulating system, such as is used in connection with internal combustion engines.

Another object is to provide an improved arrangement of valve mechanism, particularly a valve mechanism which comprises a plurality of interconnected valves which may be easily manufactured, assembled, adjusted and disassembled.

Another object is to provide effective means for manually operating valves which normally are controlled by automatic means, such as a thermostat, upon failure of the automatic means to function properly.

These, and other objects, will appear from the following description, taken in connection with the drawings which form a part of this specification, and in which:

Figure 1 is a side elevation, with portions broken away, of a power plant embodying a form of this invention;

Fig. 2 is an enlarged vertical sectional view, substantially on the line 2-2 of Fig. 1, through the circulating and regulating mechanism, also showing the driving mechanism for the pump;

Fig. 3 is a transverse section substantially on the line 3-3 of Fig. 2;

Fig. 4 is a vertical section through the valve chamber, substantially on the line 4-4

of Fig. 2, with the valve mechanism removed;

Fig. 5 is a detail view of the drain or discharge valve; and

Fig. 6 is a detail of a cam for manually operating the valve mechanism.

Referring to the drawings, 10 represents a crank case and 11 one of a plurality of cylinder blocks mounted thereon in any suitable manner in V relation, as by bolts 12. While this invention may be applied to a cooling system, the cooling medium of which is adapted to circulate in series through all of the cylinder blocks of the motor, a description of the cooling system, as applied to one block only is deemed sufficient for a clear understanding of the invention; therefore, this description will be so confined.

The cylinder block 11 is provided with the usual jacket 13, having an intake port 14, which may be arranged adjacent one end thereof. An outlet port 15 may be provided adjacent the opposite end of the cylinder block. This outlet port may then be connected, as shown, by means of the flexible branched conduit 16, 16' to a radiator 17, and valve chamber casing 18, respectively. The radiator 17 may be provided adjacent the lower part thereof with a port 19, which may be connected by means of a flexible conduit 20 with the chamber casing 18.

It will also be noted that the gas intake 21 is provided with a water jacket which is fed by a conduit 23, which is led into the upper part of the cylinder jacket, as at 24. An outlet 25 for the gas intake jacket may also be connected with the casing 18, as by the conduit 26.

While the pump mechanism and automatic control, which will be more particularly described hereinafter, is shown as arranged between the conduits 16, 16', 20, and the intake pipe 27, it is not essential that such a mechanism and control of this type be included in this system, as it will be seen this invention is applicable to thermo siphon systems, or systems adapted to be manually controlled.

The pump mechanism and automatic control, above referred to, briefly, which has

- been provided for a force feed circulating system, may comprise a pump of the well known centrifugal type, comprising a casing consisting of parts 28 and 29, which may be secured together, as by bolts 30 and mounted on the crank case 10, as by bolts 31. Suitably arranged in bearings 32 and 33 in said casing is a pump shaft 34, having an impeller 35 secured thereto, as by a pin 36.
- 10 A suitable packing box 36 is provided in the part 28 for making the same water tight at its inner side. Also arranged in the crank case 10, at opposite sides thereof, are bearings 37 for supporting a driving shaft 38,
- 15 which is arranged transversely to the motor crank shaft 39 and connected thereto for being driven therefrom, as by spiral gears 40 and 41. The shaft 38 may have a detachable connection, as by a pin and slot 20 joint 41, with the pump or impeller shaft 34.

The casing member 29 is provided adjacent its upper portion with an opening 42, over which is arranged a valve or liquid chamber 43 and secured thereto, as by bolts 25 44. This chamber, it will be seen is provided with a laterally extending inlet port 45, which is adapted to communicate with the conduit 20, as hereinabove.

It will be noted that the port 45 communicates with an inner shell 46, shown as formed integral with the chamber, this shell being provided with openings or intake ports 47 and 47' leading to the suction intake 48 of the pump mechanism and these 35 ports are adapted to be controlled by a valve mechanism, which will now be more particularly described.

It will be seen that the chamber 43 is provided at its upper side with an opening 49, over which is arranged a cover 50, which is suitably secured in position as by bolts 51. It will be seen that this cover plate 50 is provided with a port 52 and nipple 53. It will be noted that the port 52 communicates 45 with the conduit 26 from the intake jacket 22 and that the cover plate 50 has suitably secured thereto, the branched conduit 16', which is connected with the cylinder jacket outlet port 15, as heretofore described.

50 It will be noted that the casing member 29 is provided with a downwardly extending cylindrical portion 54, which serves as a journal or seat for a sliding rod or valve member 55. It will be noted also that the 55 cylindrical portion 54 is provided with a discharge port 56, which is adapted to be closed by the threaded plug 57. This port may be brought into communication with, or cut off from, a port 58 leading from the lowest part of the pump casing 28, which, also, is normally the lowest point in the entire water cooling system. The communication of the discharge port 56 and the port 58 it will be seen, is controlled by an up and 65 down movement of the valve member 55,

which is provided adjacent its upper end with a slot 59, in which may be fitted a cam 60, arranged on the shaft 61, which, it will be seen, is journaled in a sleeve 62, threaded in the boss 63 in the casing member 29. The 70 shaft 61 may be turned by its squared portion 64 and held in position by means of the collar 65, and the packing 66 which is arranged between the collar 65 and the sleeve 62, and is adapted to be jammed therebetween. It will be noted that a lock nut 67 is threaded on the collar 65, for maintaining the same in adjusted position.

75 The valve member 55 has its upper end drilled out and threaded to provide a detachable connection with an automatic control in the form of a thermostat member 68, and for supporting the same. The upper, or opposite end of the thermostat is provided with a threaded stem 69, on which may be 80 arranged upper and lower valve members 70 and 71, which may be adjustably secured in position by means of the tapered pin 72, which is threaded on the stem 69, the upper and lower valve members 70 and 71 forming 85 a balanced valve mechanism for controlling the flow of cooling medium from the conduit 16' or 20 to the chamber 43, and the suction port 48 of the pump. It will be noted that the upper valve member 70 is provided with 90 a port or bypass 73, so that when the flow of liquid through the port 45 is unrestricted; that is, when the valve members 70 and 71 are in their uppermost position, a restricted 95 flow of medium is permitted through the bypass 73. While this bypass 73 may perform several functions, the main object is to permit a circulation of water through the gas intake jacket 72, regardless of the position of the automatically controlled valve. 100

105 Having described the construction and arrangement of the various parts used in this invention, the operating of the cooling system will be understood to be as follows: Assuming the motor to be started when the cooling medium is below the desired temperature, the thermostat 68 will contract, seating the valve members 70 and 71 on their respective discharge ports 47 and 47'; thus the communication of the port 45 with the suction intake 48 of the chamber 28-29 will be cut off, and the cooling medium will be drawn in the pump through the conduit 16' and port 49, discharging it therefrom through the conduit 27 to the cylinder jacket 110 at 14, through the jacket, and discharging therefrom at the outlet 15, through the conduit 16' to the casing 18'.

115 If, when the temperature of the cooling medium rises above a predetermined degree, the thermostat 68 expands, raising the valve members 70 and 71 from their respective seats, the upper valve member restricting the flow of water through the conduit 16' and permitting water to enter the pump 120 125 125

casing from the radiator, through the port 45. When the valves are in the latter position, the cooling medium will circulate from the pump, through the same circuit as when 5 the valves are in the other positions, until the water is discharged from the jacket outlet 15, when it continues to flow to the radiator and returns to the pump casing by means of the conduit 20. Of course, as referred to above, a small quantity of water is 10 drawn through the conduit 26 from the carburetor water jacket, regardless of the position of the valve members.

Having thus described the normal operation 15 of this cooling system, it will be understood from the above description that there has been provided an automatically controlled valve, comprising members 68, 70 and 71, which may also be manually operated 20 by means of the shaft 61.

It will also be understood that there has been provided a manually operated valve member 54, which is interconnected with the automatically controlled valve, so 25 that the two of them may be operated together, and these valves are so connected that one, such as the automatically controlled valve is permitted to function independently of the valve member 54, which may be 30 manually controlled only.

In the preferred form of invention, it will be understood from what has been described that when it is desired to drain the cooling medium from the system it is only 35 necessary, after having removed the plug 57, to turn the shaft 61, raising the valve member 54 and opening all of the intake ports to the intake 48 to the suction side of the pump, and all of the water in the system 40 will be caused to drain by gravity to the lowest point in the system; namely, the port 56. On the other hand, it will be seen that the discharge valve is so interconnected with the other valves that the drain port may not 45 be opened without at the same time opening all other ports and conduits leading to the drain port, so that there is no danger of not fully draining the entire system, so long as the drain port valve only is open.

50 It will, of course, be understood that the usual vent for the radiator may be arranged in the cap, as at 74.

While I have shown and described a preferred form of my invention, it will, of 55 course, be understood that various modifications and changes may be made, by one skilled in the art, without departing from the spirit and scope of my invention.

Having thus described my invention, what 60 I claim and desire to secure by Letters Patent is:—

1. In a liquid chamber provided with an inlet and a drain port, in combination with valves for controlling said ports, of means 65 connecting said valves whereby the inlet

port is always opened when said drain port is opened.

2. In a liquid chamber provided with a plurality of inlet ports and a discharge port, in combination with valve means for controlling said ports, of means connecting said valve means whereby all of said inlet ports are opened when said discharge port is 70 opened.

3. In a liquid circulating system, the combination with means for circulating the cooling medium, a plurality of inlets feeding to said circulating means, valves for controlling said inlets, said circulating means being provided with a drain port and a valve 75 controlling said port, of means connecting said valves whereby all of them are opened when said drain port is opened.

4. In a liquid circulating system, the combination with a chamber located at the lowest level in said system, said chamber being provided with a plurality of ports, and valves for controlling the passage of liquid through said ports, said ports including a drain port located at the lowest point in the 80 system, of means connecting said valves whereby all the liquid in said system may flow into said chamber when said drain port is opened.

5. In a pump chamber, provided with a plurality of intake ports, a discharge port and a drain port, the combination of valves controlling the passage of liquid therethrough, thermal controlled means for operating one of said valves, and manual means 100 for operating the valve controlling the drain port, said manual means also being adapted to control said other valves so that all ports to the chamber are open when said drain port is open.

6. The combination, in a pump chamber provided with an inlet port and a discharge port arranged in the upper part thereof, of a valve for controlling said inlet port, a thermostat in said chamber operating said 110 latter valve, said chamber being also provided with a drain port arranged in the lowest part thereof, a valve for controlling said drain port, and manually controlled means for opening said latter valve and said 115 former valve independently of the action of the thermostat.

7. The combination, in a pump chamber provided with an inlet port and a discharge port arranged in the upper part thereof, of 120 a valve for controlling said inlet port, a thermostat in said chamber operating said valve, said chamber being also provided with a drain port arranged in the lowest part thereof, a valve for controlling said drain port, a rod connecting said valves, and means for manually controlling said valves.

8. The combination, in a pump chamber provided with an inlet port and a discharge port arranged in the upper part thereof, of 130

- a valve for controlling said inlet port, a thermostat in said chamber operating said valve, said chamber being also provided with a drain port arranged in the lowest part 5 thereof, a valve for controlling said drain port, a rod connecting said valves, and means for manually controlling said valves independently of the action of said thermostat.
9. In a liquid chamber having a port, the 10 combination of a valve for said port, a thermostat for operating said valve, and means for effecting a relative adjustment between said valve and thermostat.
10. In a liquid chamber having a port, the 15 combination of a valve for said port, a thermostat for operating said valve, means for effecting a relative adjustment between said valve and thermostat and means for adjusting the position of said thermostat.
- 20 11. In an internal combustion engine, the combination with a cylinder jacket, a radiator, a conduit connecting the radiator inlet with the jacket outlet, of a chamber having a plurality of inlet ports and a discharge 25 port, a by-pass around said radiator connected with one of said inlet ports, a conduit connecting the radiator with another inlet port, valve means for controlling said ports, means coöperating with said first means 30 whereby all of said inlet ports are opened when the discharge port is open, and means connecting said chamber with the jacket inlet.
12. In an internal combustion engine, the 35 combination with a cylinder jacket, a radiator, a connection between the radiator inlet and the jacket outlet, of a pump chamber having a plurality of inlet ports, a connection between the radiator outlet and one of 40 said inlet ports, a by-pass around said radiator and connected with another of said inlet ports, said chamber also having a discharge port arranged at the lowest point in the circulating system, valve means for controlling all of said ports, means coöperating with said first means whereby all of said inlet ports are open when the discharge port is open, and a connection between said chamber and the jacket inlet.
- 50 13. In an internal combustion engine, the combination with a cylinder jacket, a radiator, a connection between the radiator inlet and the jacket outlet, of a chamber having a plurality of inlet ports, a connection between the radiator outlet and one of said 55 inlet ports, a by-pass around the radiator connected with another of said inlet ports, said chamber also having a discharge port arranged at the bottom portion thereof,
- 60 valves for controlling said ports, a connection between the chamber and the jacket inlet, and manually operated means for simultaneously opening said valves.
14. In an internal combustion engine, the 65 combination with a cylinder jacket, a radi-
- ator, a connection between the radiator inlet and the jacket outlet, of a chamber having a pair of inlet ports, a connection between the radiator outlet and one of said inlet ports, a by-pass around the radiator and connected with the other of said inlet ports, said chamber having a discharge port arranged at the bottom portion thereof, a connection between the chamber and the jacket inlet, valves for controlling said ports, manually operated means for simultaneously opening said valves, and thermostatically operated means for operating one of said valves independently of the other.
15. In an internal combustion engine, the 80 combination with a cylinder jacket, a radiator, a connection between the radiator inlet and the jacket outlet, a chamber provided with a plurality of inlet ports and a discharge port, and valves for controlling the 85 passage of liquid therethrough, of thermo-controlled means for operating an inlet valve, manually operated means for operating the valve controlling the drain port, said manual means also being adapted to control 90 said other valves, so that all inlet ports in the chamber are open when the discharge port is unrestricted, a connection between the radiator outlet and one of said inlet ports, a by-pass around said radiator and 95 connected with the other inlet port, and a connection between the chamber and the jacket inlet.
16. In an internal combustion engine, the combination with a cylinder jacket, having 100 an inlet port and an outlet port, a radiator, connections between said radiator and said 105 ports, a by-pass around said radiator, valve means for regulating the circulation through said radiator and by-pass respectively, and a drain port arranged in the lowest part of the circulating system, means for opening and closing said drain port, said means being connected with said valves, whereby all paths to said drain port are open when the 110 drain port is open.
17. In an internal combustion engine, the cooling system comprising a cylinder jacket, having an inlet port and an outlet port, a radiator, connections between the radiator and said ports, a by-pass around said radiator, valve means for controlling the circulation through the radiator and by-pass respectively, said system being provided with a drain port, arranged at the lowest point 115 therein, and a valve therefor, of means connecting said valves whereby all are opened simultaneously.
18. In an internal combustion engine cooling system, the combination with a cylinder 120 jacket having an inlet port and an outlet port, a radiator, connections therebetween, a by-pass around said radiator, valve means for controlling the circulation through said radiator and by-pass respectively, thermo- 125
- 130

static means for operating said valve means, said system being provided with a drain port arranged at the lowest point therein, said drain port being adapted to be manually controlled, and means connecting said valves whereby all may be opened at the same time.

In testimony whereof I affix my signature in the presence of two witnesses.

LYLE K. SNELL.
